METALLIC RAILWAY TIE

Filed April 6, 1929

INVENTOR:

RAYMOND L. VARE,
BY *Attala E. Wright,
Attorney.*

UNITED STATES PATENT OFFICE

RAYMOND L. VARE, OF GERMANTOWN, PENNSYLVANIA

METALLIC RAILWAY TIE

Application filed April 6, 1929. Serial No. 352,953.

It is the object and effect of my invention to provide a metallic tie formed of comparatively thin plates of wrought metal, preferably low carbon steel, or iron, which are so assembled and united by welding their edges as to afford the maximum degree of rigidity with the minimum amount of metal.

An adjunctive feature of my invention is a rail chair plate, which may be welded in integral relation with the tie aforesaid, or be used separately in connection with a wooden tie and having means for adjustably rigidly securing a rail in proper spaced relation thereon and in electrically insulated relation therewith. Such chair plates are adapted to cooperate with lever clamp blocks which are respectively fulcrumed upon the outer upper edges of the ends of said plates; said plates having screw sockets extending vertically therein local to each clamp block and adapted to receive cap screws for pressing the clamp blocks downwardly upon the rail flanges. Said plates also have screw sockets extending horizontally in the ends thereof adapted to receive cap screws which bear upon the outer ends of the respective clamp blocks; whereby said blocks may be adjusted transversely to the rails, to properly space the latter.

My improved rail clamping means also include a locking plate whereby both of the cap screws local to each block may be prevented from rotating from the position to which they are adjusted but which may be readily released to permit said screws to be further adjusted.

My invention includes the various novel features of construction and arrangement hereinafter more definitely specified.

In said drawings; Fig. I is a perspective view of a railway tie embodying my invention, including a pair of railway chair plates integrally connected therewith.

Fig. II is a transverse sectional view of said tie, taken on a vertical plane indicated by the section line II, II in Fig. I.

Fig. III is a fragmentary side elevation of a portion of the tie shown in Fig. I, with a chair plate and its appurtenances thereon engaging a rail in adjusted position.

Fig. IV is a plan view of one of the screw locking plates shown in Fig. III.

Fig. V is an end view of said locking plate.

Fig. VI is a perspective view of a modified form of chair plate, having holes for lag screws to connect it with a tie and having calks adapted to be imbedded in such tie.

Referring to the form of my invention shown in Figs. I to V inclusive; the metallic tie 1 includes the base plate 2, preferably having the longitudinal channel 3 and laterally extending plane flanges 4 above said channel, throughout its length. Said tie also includes pairs of longitudinal metal outer strut plates 5 and inner strut plates 6 which are primarily separate from said base plate 2 but are connected therewith by respective longitudinal welded joints 7 and 8 with all of said strut plates upwardly and inwardly inclined, as shown in Fig. II. Said plates 5 and 6 are connected with the cap plate 10 by welded joints 11 at opposite edges of said cap plate and coextensive therewith.

The pair of rail chair plates 12 are precisely alike and are spot welded to said cap plate 10 and rigidly connected with the outer strut plates 5 of the tie by welded joints 13, in properly spaced relation with reference to the gauge of the railway, as indicated in Fig. I. Said chair plates 12 not only thus serve to precisely locate the rails on the ties but, as shown in Fig. II; said chair plates 12 thus cooperatively connect said outer strut plates 5 against relative movement, at the regions of the tie 1 which are subjected to the greatest stresses tending to deform it. Each of said chair plates 12 has, at opposite ends thereof, similar fulcrum ribs 14. Each such plate 12 also has two screw sockets 16 extending vertically therein respectively near the opposite ends thereof, and two screw sockets 17 extending horizontally therein at the opposite ends thereof; all of said screw sockets being conveniently intermediate of the width of the plates, as indicated in Fig. I.

I prefer to provide the screw sockets 16 with conical rims 18 at the upper ends thereof to shed water outwardly from the threads of the screws 20 which are fitted therein. Each of said chair plates 12 is provided with a

pair of lever clamp blocks 22 which are fulcrumed upon said ribs 14 and adapted to be drawn downwardly by said screws 20 which extend thru slots 23 in the respective blocks. 5 Said blocks 22 have bifurcated outer end flanges 24 adapted to receive, between their bifurcations, respective set screws 26 which extend in said screw sockets 17 in the plates 12 and are adapted to adjust said blocks 22 10 transversely to the base flanges 28 on the rails 30. Said blocks 22 have respective flanges 31 near their inner ends which depend in opposition to the side edges of the rail flanges 28 and determine the position of said 15 rails.

15 In order to electrically insulate said rails 30 from said chair plates 12; I prefer to provide each such plate with a pad of insulating material 32. Each of said blocks 22 is also 20 electrically insulated from the adjoining rail flange 28, by an angular pad of insulating material 34, interposed as shown in Fig. III.

In order to prevent accidental displacement 25 of said screws 20 and 26 from any position to which they may be adjusted; I prefer to provide them with locking plates 36, each of which has an opening 37 fitted to the head of the local cap screw 20, and has a notch 38 fitted to the head of the local set screw 26. 30 Each of said plates 36 is normally in the shape shown in full lines in Figs. IV and V; in which shape it may be readily fitted downwardly over the heads of both of said screws 20 and 26, as indicated in Figs. III and V. 35 Thereupon, the prongs 40 on said locking plates 36 may be bent inwardly to prevent the respective locking plates from being accidentally dislodged upwardly; thus preventing rotation of both screws. However, 40 said plates 36 are made of metal, preferably mild annealed steel, so far flexible that said prongs 40 may be rebent outwardly from the position indicated in dotted lines in Fig. V to the position shown in full lines in said 45 figure, to permit the removal of the lock plates 36 thus released, and permit further adjustment of said screws 20 and 26, when necessary, or if it is desired to remove the local clamp block 22 or rail 30.

50 Referring to Fig. VI; rail chair plates 42, otherwise resembling said chair plates 12, have a plurality of holes 43 extending therethru, for lag screws to engage them with wooden ties, and have a plurality of calks 45 55 and 46, projecting downwardly therefrom, in transverse relation with each other, and adapted to be imbedded in the wooden tie to which the plate is connected; so as to prevent accidental lateral displacement of the 60 plate 42. It is to be understood that such plates 42 may be equipped with clamp blocks 22 secured by screws 20 and 26, as above described.

Moreover, altho I prefer to form the tie 65 base plate 2 with an intermediate longitudi-

dinal channel 3 and to close the opposite ends of the ties with closure plates 48 which are welded in integral relation with said plates 2, 5, and 10; said base plate 2 may be made plane and said end closure plates may be omitted, and said inner strut plates 6 may be terminated at the outer ends of the chair plates 12, instead of being coextensive with the strut plates 5, in order to lessen the cost of construction of my improved tie. Moreover, other locking means may be employed in lieu of the plates 36.

Therefore, I do not desire to limit myself to the precise details of construction and arrangement herein set forth, as it is obvious that various modifications may be made therein without departing from the essential features of my invention, as defined in the appended claims.

I claim:

1. In a metallic railway tie, the combination with outer upwardly converging strut plates; of inner upwardly converging strut plates secured at their upper edges to said outer plates and having their lower edges in spaced relation with each other and with said outer plates; and a base plate connected with the lower edges of said strut plates; whereby each of said outer plates is obliquely braced by one of said inner plates.

2. A structure as in claim 1, including welded joints connecting said plates.

3. A tie structure as in claim 1; including a cap plate connected with the upper edges of said strut plates.

4. A tie structure as in claim 1; having rail securing means at the top thereof.

5. A tie structure as in claim 1; having rail securing means at the top thereof, including chair plates rigidly connected with said strut plates and bridging the outer strut plates.

6. A tie structure as in claim 1; having rail securing means at the top thereof, including chair plates rigidly connected with said strut plates and bridging and cooperatively connecting said outer strut plates against relative movement at the regions of the tie which are subjected to the greatest stresses; and lever clamping means carried by said chair plates.

7. A tie structure as in claim 1; having rail securing means at the top thereof, including chair plates rigidly connected with said strut plates and bridging and cooperatively connecting said outer strut plates against relative movement at the regions of the tie which are subjected to the greatest stresses; lever clamping means carried by said chair plates; and screw means adjustable longitudinally with respect to the tie and adapted to determine the spaced relation of the rails on said chair plates.

8. A tie structure as in claim 1; wherein the base plate has a channel intermediate of

its width and extending longitudinally with respect to the tie.

9. A tie structure as in claim 1; wherein the base plate has a channel intermediate of its width and extending longitudinally with respect to the tie; and laterally extending flanges at the upper portion of said channel; said flanges being respectively rigidly connected with the lower edges of the outer strut plates.

10. A tie structure as in claim 1; wherein the base plate includes a channel with upwardly diverging sides extending in contact with the lower edges of the inner strut plates, and the lower edges of said strut plates are joined to the sides of said channel by metal welded on said channel walls and forming step sets for said strut plates.

11. A metallic railway tie including a base plate having a downwardly extending channeled portion intermediate of its width; and flanges extending transversely to the length of said tie at the top of said channel.

In testimony whereof, I have hereunto signed my name at Philadelphia, Pennsylvania, this fifth day of April, 1929.

CERTIFICATE OF CORRECTION.

Patent No. 1,754,917.

Granted April 15, 1930, to

RAYMOND L. VARE.

It is hereby certified that error appears in the printed specification of the above numbered patent requiring correction as follows: Page 3, line 18, claim 10, for the word "sets" read "seats"; and that the said Letters Patent should be read with this correction therein that the same may conform to the record of the case in the Patent Office.

Signed and sealed this 13th day of May, A. D. 1930.

(Seal)

**M. J. Moore,
Acting Commissioner of Patents.**
